UNITED STATES PATENT OFFICE.

FRANK W. YARDE, OF ROCK FALLS, ILLINOIS.

CRANKING DEVICE.

1,171,574.

Specification of Letters Patent. Patented Feb. 15, 1916.

Application filed July 28, 1914. Serial No. 853,689.

To all whom it may concern:

Be it known that I, FRANK W. YARDE, citizen of the United States, residing at Rock Falls, in the county of Whiteside and 5 State of Illinois, have invented certain new and useful Improvements in Cranking Devices, of which the following is a specification.

My invention relates to improvements in 10 starting devices for internal combustion engines; particularly the engines of automobiles.

An object of the invention is to provide a means mounted on and adjacent the auxiliary crank shaft of the engine for imparting thereto the movement necessary to a cranking operation, said means being such in its nature as to be actuated from a point adjacent the driver's seat.

20 The invention, as a further object, contemplates a cranking device manually operable against the tension of suitable springs, the latter being so arranged relatively to the device as to automatically re-adjust the 25 several parts or elements thereof immediately subsequent to a cranking operation, thus permitting, if necessary, a repeated operation of the cranking means.

The above and additional objects are 30 accomplished by such means as are illustrated in their preferred embodiment in the accompanying drawings, described in the following specification and then more particularly 35 pointed out in the claims which are appended hereto and form a part of this application.

In describing my invention in detail reference will be had to the accompanying drawings wherein like characters denote like or 40 corresponding parts throughout the several views, and in which:

Figure 1 is a side elevation of the engine starter, a part of the supporting means therefor being shown in section; Fig. 2 is a 45 top plan view of the device as illustrated in Fig. 1; Fig. 3 is an inverted plan view of the operating gear; Fig. 4 is a top plan view of the gear supporting plate; and Fig. 5 is a detail elevation of the guide screw.

50 Referring now to the drawings by numerals, 1 designates, in section, that part of the automobile through which the auxiliary crank shaft 2 of the engine extends and to

which the supporting plate 3 of the starting device is attached. Said supporting plate 55 3 is provided with a right angled extension 4 having openings 5 formed therein, said openings being widely spaced apart and adapted for the reception of retaining means 5 bolted as at 6 to that portion 1 of 60 the machine.

As shown to advantage in Fig. 4, the supporting plate 3 is concentrically slotted as indicated at 7, through which slot a guide screw 8 extends, the said screw having 65 mounted loosely thereon an operating gear 9 disposed to operate in a substantially horizontal plane. The top face of the gear is provided with teeth 10 so shaped or beveled as to form, when taken in connection with a 70 flange 11 a peripheral groove within which is fitted a suitable flexible operating element designated 12. Guide screw 8 is threaded throughout the greater portion of its length and serves as a shaft for the operating gear 75 9, said screw passing through the slot 7 aforesaid, suitable means such as indicated at 13 serving to maintain the screw in place. An eye 14 is formed upon the upper end of the screw, the eye forming a bearing for the 80 shaft 2, pins 15 passing through the shaft preventing longitudinal movement thereof independently of like movement on the part of the screw.

Mounted on shaft 2 and meshing with the 85 teeth 10 of the gear 9 is a comparatively small beveled gear 16, said gear being maintained in mesh through the medium of a spring 17 arranged to embrace the said shaft and to abut respectively the gear and that 90 portion of the machine designated 1 through which the said shaft extends.

The under face of the operating gear 9 is recessed as shown to advantage in Fig. 3, the recess serving as or providing a housing 95 for a coiled spring 18 arranged therein, one end of the spring being attached as at 19 to the pin 8 acting as the shaft and the opposite end being attached as at 20 to the inner wall or the recess wall of the gear. 100

When it is desired that shaft 2 be turned during a cranking operation, element 12 is pulled by grasping handle 21 therefor, the latter being positioned conveniently preferably adjacent the driver's seat in the machine. By exerting a pull upon the said 105

element 12, it is apparent that the operating gear 9 will be simultaneously rotated and bodily moved longitudinally of the supporting plate 3 throughout the length of the slot 7 therein, the engagement between the pin 8 and one of the slot terminals serving as a stop means therefor.

Movement of the gear 9 circumferentially will impart a like movement to the gear 16, 10 and, the latter being mounted on shaft 2, it is apparent that the latter will be turned. During longitudinal movement of the gear 9, gear 16 is bodily moved against tension of spring 17, causing the said spring to be 15 depressed as the shaft 2 is turned. Immediately upon releasing element 12, the same having been pulled sufficiently to cause the shaft 2 to be effectually turned, spring 17 will automatically disengage the said shaft 20 2 with the clutch means (not shown) on the crank shaft of the engine, at the same time bodily return the operating gear 9 to its normal position, while the coiled spring 18 will reversely rotate the said operating 25 gear to in this manner re-adjust or re-set the starting mechanism to its normal inoperative position so as to be subsequently actuated should the first actuation prove ineffectual in causing the engine to start. The 30 pressure exerted upon element 12 must be sufficient to rotate gear 9 against tension of coiled spring 8 and to bodily move the two gears, particularly gear 16 against tension of spring 17. As an auxiliary crank 35 means, lugs or projections 22 are formed upon the free end of the shaft 2, the said lugs being engageable with a crank arm, (not shown), the latter being of any suitable construction whereby motion may be 40 imparted to the shaft.

From the foregoing, taken in connection with the accompanying drawings it will be noted that the guide pin 8 serves as a bearing for the said shaft 2 and that the latter in turn serves as a means whereby the said pin is held against rotation; that the re-adjusting or re-setting operation when taken immediately subsequent to a cranking operation is automatic and positive, the return means being governed by the two springs 17 and 18; and that by disposing the spring 18 in a recess therefor of the gear 9, the said spring is housed to in this manner prevent dust and dirt from settling 55 and accumulating therein.

In reduction to practice, I have found that the forms of my invention, illustrated in the drawings and referred to in the above description, as the preferred embodiment, 60 is the most efficient and practical; yet realizing that the conditions concurrent with the adoption of my device will necessarily vary, I desire to emphasize the fact that various minor changes in details of construction, proportion and arrangement of

parts may be resorted to, when required, without sacrificing any of the advantages of my invention, as defined in the appended claims.

Having thus fully described my invention, 70 what I claim as new and desire to secure by Letters Patent, is:—

1. In a cranking device for internal combustion engines, a shaft movable axially, a gear upon said shaft, a spring engaging the 75 gear, a second gear in mesh with said first gear, a shaft for said second gear, a coil spring secured to the shaft and to the second gear, said second gear being provided with a peripheral groove, an operating element secured to the second gear and operating within the groove to rotate the gear against tension of the coil spring, said coil spring having a greater resisting power than said first mentioned spring to provide 80 for axial movement of the shaft previous to turning movement of said second gear, as and for the purpose set forth.

2. In a cranking device for internal combustion engines, an operating gear provided 90 with a peripheral groove, a shaft upon which said gear is loosely mounted, a support for the gear having a slot formed therein through which said shaft extends, an operating element coiled about said gear 95 and fitting said groove to rotate, when pulled, said gear, a means within said gear to resist such movement, and means engaging with said gear for cranking the engine in the manner stated.

3. In a cranking device for internal combustion engines, an operating shaft, a first gear upon said shaft, a spring engaging the first gear and embracing said shaft, the said spring normally maintaining the said operating shaft in an inoperative position, a second gear having a vertical axis and in mesh with said first gear, said second gear being further provided with a peripheral groove, a shaft for said second gear, a support for the gear and the shaft, said support having an elongated opening formed therein through which the vertical shaft extends, an operating element secured to the second gear and operating in the groove aforesaid, 110 a coil spring secured to the shaft and to the second gear, the said coil spring having a greater resisting power than the spring first mentioned to provide for horizontal movement of the gears and the operating shaft 115 in unison previous to a turning movement of the gears caused by the application of a pull upon said operating element.

4. In a cranking device for internal combustion engines, a crank operating shaft movable axially into and out of engagement with the crank shaft of the engine, a first gear upon said crank operating shaft, means urging said gear and said crank operating shaft axially out of engagement with said 125

crank shaft, a second gear in mesh with said first gear, a flexible element coiled about said second gear and operable to rotate it and the crank operating shaft to bodily move said shaft into engagement with the crank shaft, a means resisting movement of the element in the manner stated, and a means to limit bodily move-

ment of said gear and said crank operating shaft, substantially as described.

In testimony whereof I affix my signature in presence of two witnesses.

FRANK W. YARDE.
